UNITED STATES PATENT OFFICE

GUY T. SEIDLE, OF LOS ANGELES, CALIFORNIA

DESIGN FOR AN ASH TRAY

Application filed October 22, 1930. Serial No. 37,349. Term of patent 3½ years.

To all whom it may concern:

Be it known that I, GUY T. SEIDLE, a citizen of the United States, residing at Los Angeles, in the county of Los Angeles and State of California, have invented a new, original, and ornamental Design for an Ash Tray, of which the following is a specification, reference being had to the accompanying drawing, forming part thereof, in which:

Fig. 1 is a side elevation of an ash tray showing my new design;

Fig. 2 is a top plan view of the same; and
Fig. 3 is a transverse section on the line

3—3 of Fig. 1.

I claim:

The ornamental design for an ash tray, as shown.

GUY T. SEIDLE.
